VACUUM CLEANER

Gustaf E. Lofgren, Riverside, Conn., assignor to
 Electrolux Corporation, Old Greenwich, Conn.,
 a corporation of Delaware

Application July 18, 1945, Serial No. 605,778

7 Claims. (Cl. 183—35)

1

This invention relates to vacuum cleaners and is particularly concerned with problems of dirt and dust collection and disposal in connection therewith.

One persistently difficult problem in the art of vacuum cleaning is that of dirt disposal. Vacuum cleaners of both the "bag-on-handle" type and the "tank" type, as now in common use, require the removal of the dust collecting bag from the machine and the emptying of the dirt therefrom at periodical intervals. No commercially successful means has yet been devised by which this tedious and unpleasant task may be avoided. In both types of cleaners, the disconnection of the bag from the cleaner and the transportation of the bag to the place of final disposal as well as the emptying operation are not only difficult and tedious but the operator is rendered liable to contamination by the dirt and dust accumulated by the bag during such manipulations.

It is among the prime objects of the present invention to provide novel and improved means whereby the discharge of accumulated dirt from the vacuum cleaner may be provided for with a minimum of difficulty and labor and with a minimum of liability with respect to soiling of the operator.

Further object of the invention is to provide a vacuum cleaner having mechanical means readily operated to compress the accumulated dirt thereof into a conveniently dischargeable container.

Still further object of the invention is to provide a tank type vacuum cleaner having means associated therewith for removing accumulated dirt thereof without requiring the removal of the dirt collecting fabric.

A still further object of the invention is to provide a novel and improved vacuum cleaner assembly which embodies several advantageous features in a single combined structure which is both readily operated, controlled and well suited to the demands of economic manufacture.

It is a further object of the invention to provide a vacuum cleaner having a dust receiving compartment which may be periodically cleared of foreign matter without the necessity of discharging the matter from the casing, thus the arrangement is such that during the normal cleaning operations the cleaning operation may be temporarily discontinued, the screen vibrated to loosen accumulated dirt and the dust chamber emptied so as to maintain maximum cleaning efficiency without the necessity of removing accumulated dirt from a dirt receptacle into which

2

it has been compressed by the chamber ejecting means.

Numerous other features and objects of the present invention will be apparent from the following specification when taken in conjunction with the accompanying drawings, in which:

Fig. 1 is a top plan view of one embodiment of the present inventive concept;

Fig. 2 is a vertical longitudinal section of that form of the invention illustrated in Fig. 1, taken on the line 2—2 of that figure;

Fig. 3 is a fragmentary horizontal longitudinal section taken on line 3—3 of Fig. 2;

Fig. 4 is a fragmentary section taken on the line 4—4 of Fig. 1, and

Fig. 4 is a detailed section taken on the line 5—5 of Fig. 2.

The present embodiment of the invention is shown as applied to tank type vacuum cleaners which are characterized by the provision of a suitable housing within which is mounted a motor-fan assembly in combination with a fabric dust screening member. The structural embodiment of the present inventive concept is shown as provided with means by which suction may be diverted from flowing through the screen and simultaneously therewith the screen may be agitated to dislodge clinging dirt therefrom. The primary inventive concept may be defined as the provision of a reciprocable ram mounted for movement through a dust receiving chamber beneath the screen in such manner as to eject dirt from the chamber and compress the same into an associated removable receptacle. In the form of the invention here shown the ram is conveniently actuated by a foot treadle and the air which is drawn through the apparatus by the motor is admitted under the screen by a passageway extending through the ram structure. The full inventive concept also embraces the entire structural arrangement and the combination by which there is provided an agitator in conjunction with the ram and removable receptacle.

Referring now more particularly to the drawings the herein disclosed embodiment of the invention comprises a casing 10 which is generally rectangular in configuration. In the casing 10, there is disposed a motor-fan unit 11, the circuit to which may be suitably controlled by a switch actuator 12, current being supplied thereto from a conductor 13 which is mounted upon a cord reel 14 disposed within a compartment 15 located beneath the motor. Suitable means, preferably of a resilient nature, are provided to normally wind the conductor upon the reel so as to elimi-

nate the necessity of manually winding or otherwise disposing of the conductor externally of the machine when the device is not in operation. The motor-fan unit, which is preferably resiliently mounted within the casing 10 by means of a supporting gasket 16, is provided with a forwardly extending casting 11 which is centrally apertured to admit air therethrough and to the unit. An air filter 18 is provided to filter from the air any fine dust particles which may have penetrated the interstices of the primary filter screen. Air which is so drawn through the unit is discharged to the atmosphere through a suitable exhaust opening 19 centrally located in the rear end of the casing above the cord reel compartment.

A motor shaft 20 extends forwardly from the motor and through the filter 18 and is provided within a portion of the casting 11 with a worm 21 cooperating with a worm gear 22 which, through a clutch mechanism 23, selectively drives a gear 24 which, by an intermediate pinion 25, rotates a gear 26 which is mounted upon a shaft 27, which shaft also carries an eccentric 28 and a counterbalance weight 29. Eccentric 28 is mounted within a ring 30 whereby rotation of the eccentric will impart oscillatory vibration to the dust collecting screen supported by the ring as hereinafter described. The clutch 23 is adapted to be engaged so as to transmit rotation from the shaft 20 to the shaft 27 by the application of foot pressure to a button 31 which is normally maintained in raised position by a spring 32. As shown in Fig. 4, button 31 is mounted upon a transverse actuator bar 33 having a depending clutch actuating projection 34. The ends 35 of the bar engage arms 36 of pivotally mounted hinges 37 to which are attached vent doors 38 normally covering vent apertures in the casing 10. The projection 34 bears against the upper end of a clutch pin 39 which is normally urged upwardly against the projection 34 by the spring 40 and which is connected to the gear 24 for rotation therewith by a transverse pin 41. The clutch pin 39 also carries a hub 42 which has a projection 43 which, when depressed, engages a pin 44 mounted in a driving clutch hub 45 which in turn is mounted upon and rotated by a shaft 46 carried by the worm gear 22.

From this construction it will be seen that upon depression of the button 31, the vent doors 38 will be opened to permit air to pass directly to the motor fan unit 11 from the atmosphere, thus cutting off suction through the screen, and at the same time the clutch will be engaged to cause rotation to the shaft 27 and its eccentric 28, which rotation will impart the desired vibration to the dust screen.

The screen preferably used in the present construction is of the reentrant type comprising a pair of substantially concentric frustoconical sections, the outer and larger section 50 having its open end secured as by a band 51 to an air inlet ring 52. The upper or smaller end of the section 50 is secured by band 51A to member 30 from which the smaller or inner section 53 extends downwardly and beneath a plate 54 in which the shaft 27 has a bearing as at 55, tension applied to the screen during its application being such as to retain the member 54 against the shaft 27. By this construction it will be seen that when the eccentric 28 on shaft 27 imparts bodily rotary movement to the member 30, such movement will cause a vigorous vibration of both sections of the screen and since such vibration is imparted

only when the button 31 is depressed and thus only when the doors 38 are open, accumulated and clinging dust will be shaken from the screen. It is important to note that the doors are open during the shaking operation since otherwise air would be continuously drawn through the screen during its vibration and it has been found that in such an event the vibration will not be effective in loosening adhering dirt.

10 Beneath the inlet ring 52 there is provided a dust receiving chamber 60, the rear end of which under the cord reel 14 is open as indicated at 61 and removably receives thereover a removable dust receptacle 62, the open mouth of which is 15 normally sealed against a gasket 63 when the receptacle is in position. The receptacle is retained in such position and sealed against the gasket 63 by a latching mechanism including pairs of parallelogram arms 64 and 65. The arms 64 are pivoted as at 66 in the brackets 67 secured to the rear wall of the machine and the arms 65 are similarly pivoted as at 68. The arms 65 carry with them companion arms 69 to which are applied clamping rollers 70. The arms 64 and 65 are joined at their free ends by a handle arm 71 which extends beyond the arms 65 to provide an actuating handle 72 which in cooperation with the recesses 73 in the receptacle 62 permits manipulation of the handle arm to swing the arms 64 and 65 outwardly to release the clamping members 70 and permitting removal of the receptacle. At least one of the arms 65 is further provided with a projection 74 which limits the pivotal movement of the arms 64 and 65.

35 As shown in Fig. 2, the bottom wall of the casing 10 terminates at the opening 61 of the dust receiving chamber 60, and from this point rearwardly the casing is open at the bottom, the lowermost permanent wall at this place being that between the motor-fan unit 11 and the cord reel 14. In order to remove the receptacle 62, the cleaner is stood up on its exhaust end and the handle 72 is pulled outwardly and downwardly so as to pivot the arms 64, 65 and 69 counterclockwise. This moves the rollers 70 away from the receptacle 62, thus permitting the latter to be moved downwardly a sufficient distance for its upper end to clear the open end 61 of chamber 60. Thereafter, the receptacle 62 may be moved outwardly from 50 between the side walls of the casing 10, the handle 72 having been moved downwardly far enough, before projection 74 contacts arm 64, to permit the bottom of the receptacle to clear the handle. The receptacle may then be emptied and replaced, 55 the handle 72 being moved upwardly and inwardly to cause the rollers 70 to bear against the closed end of the receptacle to thus force the open end against the gasket 63.

Within the opposite or forward end of the 60 chamber 62 is mounted a combined inlet conduit and ram, a perpendicular end wall 75 of which constitutes the ram surface, packing material 76 being provided on the sides and bottoms thereof to seal the same. Forwardly of the wall 75 65 the member is provided with a downwardly inclined and forwardly extending air conduit 77 which encircles a fixed air inlet conduit 78 which communicates with a suction hose receiving fixture 79. Packing 80 is provided between the conduits 77 and 78 to prevent air leakage therebetween and top packing element 81 is provided to seal the inner end of the conduit 77 by engagement with the top wall 82 of this unit.

As indicated more particularly in Figs. 2 and 5 75 of the drawings, the ram including surface 75

and air inlet conduit 77 as well as the forwardly extending side walls constitutes a single unit which is guided for reciprocating movement through the chamber 60 by the engagement of its packing material 76 with the walls of the chamber 60 and by the encirclement of the conduit 77 over the fixed air inlet 78.

In the normal operation of the cleaner it will be seen that with the motor operating and a suction hose and cleaner nozzle applied to the fixture 79, air will be drawn in through the tube 78 and conduit 77 and will thus be drawn through the screen sections 50 and 53 and exhausted through the motor and exhaust outlet 19. Heavy dirt particles entrapped by the inflow of air will be prevented from passing through the screen and will drop downwardly in front of the ram surface 75 into the chamber 60. Some lighter particles of dust and dirt may cling to the screen until such time as the screen is vibrated and the air suction bypassed to the motor through the doors 38, at which time such particles will also drop into the compartment 60 in front of the ram. It will be noted that the air which is admitted through conduit 77 is directed upwardly and away from chamber 60, whereby there is a minimum disturbance of the air in this chamber so that agitation of dust already therein is avoided.

For actuating the ram, the upper portion of the front of the casing is formed to provide a pair of parallel walls 85 between which extend a ram actuating shaft 86 to which is attached a foot pedal 87, the pedal being normally retained in raised position and the shaft urged in clockwise direction by a coil spring 88 which engages a hook 89 depending from the lower side of the pedal 87. Within the side members 85 and attached to the ends of the shaft 86 which extend therein is a pair of ram actuating cranks 90, each of which is connected by links 91 to the side wall of the ram and inlet unit as indicated at 92. From this construction it will be seen that in normal operation the parts are as shown in Fig. 2 with the foot pedal raised and the ram in its most forward position. When it is desired to discharge the accumulated dirt, the button 31 is first depressed whereby accumulated dust is shaken from the screen into the chamber 60 together with such heavy particles which have already dropped into it by gravity. After the desired shaking, the motor 11 is preferably deenergized by manipulation of the switch 12 and thereafter the operator's foot is applied to the pedal 87 thus rocking shaft 86 in counter-clockwise direction against the tension of spring 88. Such rocking movement of shaft 86 pivots cranks 90, their lower ends moving in an arcuate path between walls 85, thus thrusting links 91 towards the rear of the device. Through the cranks 90 and links 91 the ram is thus moved longitudinally through the chamber 60 forcing the accumulated dirt out the open end 61 and into the receptacle 62 where it is compressed. Pressure may then be relieved from the pedal 87 and the handle 72 manipulated to release the container 62 which may then be removed, emptied and subsequently reapplied, as previously described.

From a consideration of the foregoing, it will be seen that the present invention provides a novel and improved cleaner which in combination with cord reel, motor switch, air by-pass, and screen vibrator provided means for clearing the dust compartment and thrusting the dust into a removable dirt receptacle, it being understood that the compartment may be cleared many

times and the screen vibrated many times before it is necessary to remove the receptacle in which the dirt may be compressed by the repeated operations of the ram.

5 It will be understood, of course, that the invention is not limited to the various structural features here shown by way of illustration and that numerous changes and modifications thereof may be resorted to without departure from the spirit or scope of the invention as outlined in the appended claims.

What I claim is:

1. In a vacuum cleaner, means for separating entrained dirt from air, means forming a chamber for receiving the separated dirt, a removable receptacle communicating with said chamber, and a ram reciprocable within said chamber, said ram having a cross-section conforming substantially to the cross-section of said chamber whereby reciprocation of the ram discharges dirt from the chamber into said receptacle.

15 2. In a vacuum cleaner, a casing, means in said casing for separating entrained dirt from air, said casing including walls forming a chamber 25 for receiving the separated dirt, the upper wall of said chamber being formed with an inlet opening, said walls defining an outlet opening at one end of said chamber, a removable receptacle having an opening communicating with said outlet 30 opening, and a ram horizontally reciprocable within said compartment towards and away from said outlet opening, said ram having a cross-section conforming substantially to the cross-section of said chamber whereby movement of the 35 ram towards said outlet opening discharges dirt therethrough and into said receptacle.

3. In a vacuum cleaner, means for separating entrained dirt from air, means forming a chamber 40 for receiving the separated dirt, a removable receptacle communicating with said chamber, a ram reciprocable within said chamber, and manually operable means for reciprocating said ram, said ram having a cross-section conforming substantially to the cross-section of said chamber 45 whereby a single reciprocation of said ram discharges substantially all of the dirt from the chamber into said receptacle.

4. In a vacuum cleaner, means for separating entrained dirt from air, means forming a chamber 50 for receiving the separated dirt, a removable receptacle communicating with said chamber, a ram reciprocable within said chamber towards and away from said receptacle, manually operable means for moving said ram towards said 55 receptacle, and resilient means for returning said ram, said ram having a cross-section conforming substantially to the cross-section of said chamber whereby a single movement of the ram towards said receptacle discharges substantially 60 all of the dirt from the chamber into said receptacle.

5. In a vacuum cleaner, a casing, means in said casing for separating entrained dirt from air, means forming a chamber for receiving the separated dirt, a removable receptacle communicating with said chamber, a ram reciprocable within said chamber for discharging dirt therefrom into said receptacle, an inlet conduit carried by said casing and extending thereto, and a conduit 65 fixed to said ram and telescopically connected to the first-mentioned conduit whereby communication between said conduits is maintained during reciprocation of said ram and the conduit fixed thereto.

70 6. In a vacuum cleaner, a casing, means in said

casing for separating entrained dirt from air, means forming a chamber for receiving the separated dirt, a removable receptacle communicating with said chamber, a ram reciprocable within said chamber for discharging dirt therefrom into said receptacle, a foot pedal for reciprocating said ram, an inlet conduit carried by said casing and extending thereto, and a conduit fixed to said ram and telescopically connected to the first-mentioned conduit whereby communication between said conduits is maintained during reciprocation of said ram and the conduit fixed thereto.

7. In a vacuum cleaner, a casing having an inlet and an outlet, means for producing flow of air through said casing, a fabric dust separating member disposed in the path of flow of air through said casing, means for shaking said fabric to dislodge dirt therefrom, said casing including walls forming a chamber beneath said dust separating member for receiving dirt, a removable receptacle communicating with said chamber, a

ram reciprocable within said chamber for discharging dirt therefrom into said receptacle, a conduit carried by said casing and extending thereto from said inlet, and a conduit fixed to said ram and having one end telescopically connected to the first-mentioned conduit whereby communication between said conduits is maintained during reciprocation of said ram and the conduit fixed thereto, the opposite end of the second-mentioned conduit being directed upwardly and away from said chamber.

GUSTAF E. LOFGREN.
